DESIGN FOR A GLASS DISH

Albert J. Avetta, Pittsburgh, Pa.

Application July 16, 1940, Serial No. 93,674

Term of patent 14 years

To all whom it may concern:

Be it known that I, Albert J. Avetta, a citizen of the United States, residing in Pittsburgh, Allegheny County, and State of Pennsylvania, have invented a new, original, and ornamental Design for a Glass Dish, of which the following is a specification, reference being had to the accompanying drawing, forming part thereof, in which:

Fig. 1 is a top plan view of a glass dish, showing my new design; and Fig. 2 a front elevational view thereof.

I claim:

The ornamental design for a glass dish, as shown.

ALBERT J. AVETTA.
